FUSE MOUNTING

Minor William Johnson and William Thomas Hayes, Nashville, Tenn.

Application April 19, 1939, Serial No. 268,804

2 Claims. (Cl. 200—134)

This invention relates to a fuse mounting, and has for the primary object the provision of a device of this character which includes improved fuse terminal clips which will permit fuse changing to be easily and quickly carried out should a fuse burn out and which will efficiently grip the terminals of the fuse to prevent arcing when in use and consequently prolong the life of the clips as well as the terminals of the fuse and tends to check corroding.

With these and other objects in view, the invention consists in certain novel features of construction, combination and arrangement of parts to be hereinafter more fully described and claimed.

For a complete understanding of our invention, reference is to be had to the following description and accompanying drawing, in which—

Figure 1 is a front elevation illustrating a fuse mounting constructed in accordance with our invention.

Figure 2 is a sectional view taken on the line 2—2 of Figure 1, showing one of the clips.

Figure 3 is a perspective view illustrating the bifurcated portion of one of the clips and its attaching plate.

Figure 4 is a wedge element for coaction with the bifurcated portion in gripping a terminal of a fuse.

Referring in detail to the drawing, the numeral 5 indicates a panel mounting constructed of insulated material and apertured to receive fasteners for securing said panel on a support. Clips 6 are mounted on the panel 5 by screws or like fasteners 7 and are arranged a selected distance apart to receive the terminals 8 of a fuse 9, it being understood that the clips are constructed of conductive material and the fasteners 7 are employed for connecting electric leads to the clips.

Each clip includes an attaching plate 10 on which is formed an enlargement 11 including converging portions 12 and 13. Formed on the inner face of the portion 12 inwardly of the free end thereof is a shoulder 14 acting to form a seat for limiting the inward movement of the terminal of the fuse in the clip. The portion 13 is bifurcated and opening into the last-named bifurcation is a screw threaded socket 15 formed in the enlarged portion 11 to receive a set screw 16.

A wedge element 17 is adapted to enter between the portions 12 and 13 and in contact with the terminal of the fuse and has a bifurcated portion 18 disposed at right angles thereto through which the set screw 16 extends. By threading the set screw into the socket 15 the wedge element 17 will be drawn tightly inwardly between the bifurcated portions 12 and 13 forc-

ing the terminal of the fuse tightly against the seat 14 and against the portion 12, thereby establishing an efficient electrical connection between the clip and the terminal of the fuse which will prevent arcing and tends to check corrosion.

A clip of the character described and shown in the drawing is easily actuated to free the terminal of a fuse therefrom and to permit the reinstatement of a terminal of a fuse therein when desired. Also, it will be seen that due to the construction of this clip the bifurcated portions 12 and 13 as well as the seat 14 may be readily cleaned of corrosion.

The set screw 16 in its head portion may be provided with an annular groove 19 to receive the bifurcated portion 18 of the wedge 17 thereby rotatably connecting the set screw to the wedge causing the wedge to follow the movement of the set screw.

It is believed that the foregoing description, when taken in connection with the drawing, will fully set forth the construction and advantages of this invention to those skilled in the art to which such device relates, so that further detailed description will not be required.

What is claimed is:

1. A fuse clip comprising an attaching plate including an enlarged portion, said enlarged portion being cut-away to form converging portions and one of said converging portions having a bifurcation, said enlarged portion having a screw threaded socket opening out into the bifurcated portion, a shoulder formed on one of the converging portions to form a seat for a fuse terminal, a wedge element engageable with the fuse element and the bifurcated converging portion to force the fuse terminal against the other converging portion and the seat, and a set screw connected with said wedge element and threaded into said socket.

2. A fuse clip comprising an attaching plate including an enlarged portion, said enlarged portion being cut-away to form converging portions and one of said converging portions having a bifurcation, said enlarged portion having a screw threaded socket opening out into the bifurcated portion, a shoulder formed on one of the converging portions to form a seat for a fuse terminal, a wedge element engageable with the fuse element and the bifurcated converging portion to force the fuse terminal against the other converging portion and the seat, a bifurcated portion formed on said wedge element and overlying the bifurcation of the converging portion, a set screw extending through the bifurcation of the wedge and threaded into the socket.

MINOR WILLIAM JOHNSON.
WILLIAM THOMAS HAYES.
